UNITED STATES PATENT OFFICE.

WARREN A. GREENLAW, OF MELROSE HIGHLANDS, AND CHARLES F. RYAN, OF BEACHMONT, MASSACHUSETTS, ASSIGNEES TO THE GREENLAW MANUFACTURING COMPANY, OF BOSTON, MASSACHUSETTS, A CORPORATION OF MAINE.

REDUCTION-VALVE.

1,173,259.

Specification of Letters Patent.

Patented Feb. 29, 1916.

Application filed December 3, 1914. Serial No. 876,163.

To all whom it may concern:

Be it known that we, WARREN A. GREENLAW, a citizen of the United States of America, and a resident of Melrose Highlands, in the county of Middlesex and State of Massachusetts, and CHARLES F. RYAN, a citizen of the United States of America, and a resident of Beachmont, in the county of Suffolk and State of Massachusetts, have invented certain new and useful Improvements in Reduction-Valves, of which the following is a specification.

This invention relates to reducing valves adapted to regulate the pressure of water, steam, air, or other fluid.

The invention has for its object the simplification of the construction of devices of this character and at the same time to produce a valve very sensitive in operation.

The invention consists in certain novel features of construction and operation of parts which will be fully understood by reference to the description of the drawings and to the claims hereinafter given.

Of the drawings: Figure 1 represents a vertical section of a valve embodying the principles of the present invention. Fig. 2 represents a vertical section of the lower portion of the same, the cutting plane being on line 2—2 on Fig. 1. Fig. 3 represents a horizontal section of the same, the cutting plane being on line 3—3 on Fig. 1, and Figs. 4, 5, and 6 represent horizontal sections of the same, the cutting plane being on lines 4—4, 5—5, and 6—6 on Fig. 1.

Similar characters designate like parts throughout the several figures of the drawings.

In the drawings, 10 is the body portion or casing provided with an inlet opening 11 and an outlet opening 12, these openings being separated by a partition 13 having a cylindrical opening 14 extending therethrough and surrounded by a conical valve seat 15 in the upper face of said partition 13. The inlet opening 11 is provided with an inlet union coupling 16 and an outlet union coupling 17 is provided for the outlet opening 12. The casing 10 has projecting upwardly therefrom in axial alinement with the opening 14 a boss 18 having a cylindrical chamber 19 therein. A smaller boss 20 extends from the lower part of the casing 10, this boss 20 having formed there-

in a cylindrical chamber 21 in axial alinement with the opening 13 and chamber 19.

A valve 22 normally closes the opening 14 in the partition 13, this valve being elongated and extending into the chamber 19. The upper end of the valve 22 is enlarged to form a loosely fitting piston 23. The valve 22 also loosely fits the opening in the partition between the inlet opening 11 and the chamber 19. Owing to this loose fit of the upper end of the valve 22 and the piston 23 the fluid pressure admitted to the inlet opening is adapted to leak by the periphery of the valve 22 and piston 23 into the chamber 19.

The valve 22 is provided with a downwardly extending stem 24 to the lower end of which is secured a reciprocating member 25 fitting the cylindrical chamber 21. The lower end of this chamber 21 is closed by a bottom cap or plug 26 while the upper end of the chamber communicates with the outlet opening 12 by means of the passages 27. Threaded to the boss 18 is an annular cap member 28, the upper end of which fits over a flange 29 of a cap plate 30 having a cylindrical hub 31, the upper end of which is provided with a plurality of peripheral teeth 32.

Superimposed upon the upper end of the boss 18 is a cup-shaped member 33 having a hub extending downwardly into the chamber 19, this hub being provided with a plurality of radial passages 34 communicating at one end by means of the ports 35 with the chamber 19. The opposite ends of said radial passages 34 communicate with a cylindrical compartment 36 closed by the plug 37, as indicated in Fig. 1 of the drawings. The cup-shaped member 33 has a central port 38 communicating with the compartment 36 and normally closed by the controlling valve 39. The controlling valve 39 is retained to its seat by the spring 40 surrounding a hub 41 extending upwardly from the cup-shaped member 33, and bearing against the plate 42 secured to the stem 43 of the valve 39. The stem 43 is provided with a reduced portion opposite which is the mouth of an intercommunicating passage 44, the opposite end of which communicates with a chamber 21 near the bottom thereof.

Interposed between the cup-shaped mem-

ber 33 and the cap plate 30 is a diaphragm 45. Within a recess in the cap plate 30 and resting upon the diaphragm 45 is a button 46 forming the bottom seat for the adjusting spring 47 contained within the cylindrical hub 31 of said cap plate 30. The upper end of the adjusting spring 47 bears against a plate 48 forming a top seat for said spring. This plate 48 has an inwardly extending hub 10 through which extends a threaded member by which said plate is secured to the threaded adjusting member 49. This adjusting member 49 is provided with a flat-sided shank 50 having secured to its upper end a collar 51. Mounted upon the shank 50 and movable longitudinally thereof is a handle 52 provided with a groove engaging finger 53. When it is desired to adjust the tension of the spring 47 the handle 52 is raised 15 along the flat-sided shank 50 until the finger 53 disengages the peripheral grooves 32. When the finger 53 has been thus disengaged the adjusting member 49 may be turned as desired to secure the necessary tension 20 for the spring 47. When the hand is removed from the handle 52 it will move downwardly on the shank 50 and when the finger 53 is directly opposite one of the peripheral grooves 32 it will enter said groove 25 and lock the adjusting member from further rotation. When the end of the finger 53 comes into contact with the upper face of the cylindrical hub 31 the jarring of the valve will cause it to assume a position 30 immediately over one of the grooves and then enter the same as before described. The collar 51 limits the outward movement of the handle 52 and the plate 48 contacting with an internal shoulder on the upper end 35 of the cylindrical hub 31 limits the outward movement of the adjusting member 49. A passage 54 extends from the outlet opening 12 to the interior of the cup-shaped member 33 so that the under side of the diaphragm 45 is subjected at all times to the fluid pressure on the outlet side of the valve. 40

In the operation of the valve the adjusting spring is set for the required fluid pressure desired and then is locked by the engagement of the finger 53 with one of the grooves 32. This adjustment of the spring 47 will force the diaphragm 45 downwardly 45 into contact with the valve stem 43 and move the valve 39 from its seat. As the fluid pressure enters the inlet opening 11 it will pass around the loose fitting valve 22 and piston 23 into the chamber 19. This fluid pressure will pass through the ports 35 into the radial passages 34 and entering the port 38 will pass through the passage 44 into the bottom of the chamber 21, and acting upon the reciprocating member 25 will lift the valve 22 from its seat; thereby permitting the fluid pressure in the inlet opening 11 to pass through the opening 14

into the outlet opening 12. The diaphragm 45 having been set for a predetermined pressure and being subjected to the fluid pressure in the outlet opening 12 at all times, it is obvious that as soon as the fluid pressure in its outlet opening exceeds the pressure determined upon it will overcome the tension of the spring 47 and return the diaphragm 45 to its normal position, thus permitting the spring 41 to return the valve 39 to its seat closing the port 38 and preventing further flow of the fluid pressure through the passage 44 into the chamber 21. The fluid pressure in the outlet opening will then, through the ports 27, act upon the upper face of the reciprocating member 25 and return the valve 22 to its seat, this downward movement being assisted by the main valve spring 54. The member 25 is loosely fitted to the wall of the chamber 21 so that the fluid is permitted to gradually leak by said member during its downward movement. The valve will then remain closed until the fluid pressure on the outlet side of the valve has been reduced sufficiently to permit the valve 39 to be opened again. The flow of the fluid pressure from the inlet opening 11 into the chamber 19 will then cause the valve 22 to again be opened in the same manner as hereinbefore described. 95

In order to prevent a too sudden lifting of the valve 22 from its seat, baffle plates 55 are provided projecting from each side of the inlet opening 11 and adjacent to said valve. These baffle plates prevent the fluid pressure as it passes through the opening 11 surrounding the valve 22 and lifting it too suddenly. As it is with the adjacent ends of the two baffle plates slightly separated, the fluid pressure first strikes the central portion of the valve 22 and gradually lifts the same from its seat, the full force of the fluid pressure in the inlet opening having no effect upon the valve until it has been raised above the top of said baffle plates. 110

This valve is very simply constructed and is very sensitive in its operation.

It is believed that the operation and many advantages of this device will be fully apparent from the foregoing description. 115

Having thus described our invention, we claim:

1. In a device of the class described, the combination of a casing provided with inlet and outlet openings separated by a partition with a conically sealed port and having cylindrical chambers on opposite sides of said port and in axial alignment therewith connected by an intercommunicating passage terminating at the outer ends of 120 said chambers; a spring pressed valve normally closing said port and provided with a piston member loosely fitting one of said chambers; a reciprocating member fitted to the other chamber and secured to and 130

- movable with said valve; a smaller spring 5
pressed valve normally closing the passage
between said chambers; and adjustable
means for controlling the opening of said
smaller valve adapted to be influenced by
the fluid pressure in said outlet opening.
2. In a device of the class described, the
combination of a casing provided with in-
let and outlet openings separated by a par-
10
tition with a conically seated port and hav-
ing cylindrical chambers on opposite sides
of said port and in axial alinement there-
with connected by an intercommunicating
15
passage terminating at the outer ends of
said chambers; a spring pressed valve nor-
mally closing said port and provided with a
piston member loosely fitting one of said
chambers; a reciprocating member fitted to
20
the other chamber and secured to and mov-
able with said valve; a removable member
for closing the end of the first mentioned
chamber and provided with a port communi-
25
cating with said intercommunicating pas-
sage; a small valve carried by said member
for normally closing said port; and adjust-
able means for controlling the opening of
30
said small valve adapted to be influenced
by the fluid pressure in said outlet opening.
3. In a device of the class described, the
combination of a casing provided with in-
let and outlet openings separated by a par-
35
tition with a conically seated port and hav-
ing cylindrical chambers on opposite sides
of said port and in axial alinement there-
with connected by an intercommunicating
40
passage terminating at the outer ends of
said chambers; a spring pressed valve nor-
mally closing said port and provided with a
piston member loosely fitting one of said
chambers; a reciprocating member fitted to
45
the other chamber and secured to and mov-
able with said valve; a removable member
for closing the end of the first mentioned
chamber and provided with a port communi-
50
cating with said intercommunicating pas-
sage; a small valve carried by said member;
a spring also carried by said member for
normally closing said small valve; a cap
secured to said casing and surrounding said
55
removable member; and adjustable means
carried by said cap for controlling the open-
ing of said small valve adapted to be in-
fluenced by the fluid pressure in said outlet
60
opening.
4. In a device of the class described, the
combination of a casing provided with in-
let and outlet openings separated by a par-
65
tition with a conically seated port and hav-
ing cylindrical chambers on opposite sides
of said port and in axial alinement there-
with connected by an intercommunicating
70
passage terminating at the outer ends of said
chambers; a reciprocating member fitted to
the other chamber and secured to and mov-
able with said valve; a removable member
75
for closing the end of the first mentioned
chamber and provided with a port communi-
cating with said intercommunicating pas-
sage; a small valve carried by said member;
80
a spring also carried by said member for
normally closing said valve; a diaphragm
superimposed upon said removable member;
an annular flanged head superimposed
85
upon said diaphragm; an annular re-
taining member surrounding the flange of
said head and threaded to said casing; and
adjustable means carried by said head for
controlling the opening of said valve and
adapted to be influenced by the fluid pres-
90
sure in said outlet opening.
5. In a device of the class described, the
combination of a casing provided with in-
let and outlet openings separated by a par-
95
tition with a conically seated port and hav-
ing cylindrical chambers on opposite sides of said
port and in axial alinement therewith con-
nected by an intercommunicating passage
100
terminating at the outer ends of said cham-
bers; a spring pressed valve normally clos-
ing said port and provided with a piston
member loosely fitting one of said cham-
bers; a reciprocating member fitted to the other
105
chamber and secured to and movable with
said valve; a removable member for clos-
ing the end of the first mentioned chamber
and provided with a port communicat-
110
ing with said intercommunicating passage; a
small valve carried by said member; a
spring also carried by said member for nor-
mally closing said small valve; a diaphragm
superimposed upon said removable member
115
and under the influence of the fluid pressure
in said outlet opening; a member threaded
to said casing inclosing said removable
member and diaphragm and having a cylin-
drical hub; a button resting on said dia-
phragm; a plug threaded to said hub; a rev-
oluble supporting plate carried by said
120
plug; and a spring interposed between said
plate and button.
6. In a device of the class described, the
combination of a casing provided with in-
let and outlet openings separated by a par-
125
tition with a conically seated port and hav-
ing cylindrical chambers on opposite sides
of said port and in axial alinement there-
with connected by an intercommunicating
130
passage terminating at the outer side of said
chambers; a spring pressed valve normally
closing said port and provided with a pis-
ton member loosely fitting one of said cham-
bers; a reciprocating member fitted to the
135
other chamber and secured to and movable
with said valve; a removable member for
closing the end of the first mentioned cham-
ber and provided with a port communicat-
140
ing with said intercommunicating passage;

- a small valve carried by said member; a spring also carried by said member for normally closing said small valve; a diaphragm superimposed upon said removable member
 5 and under the influence of the fluid pressure in said outlet opening; a member threaded to said casing inclosing said removable member and diaphragm and having a cylindrical hub provided with peripheral
 10 grooves; a button resting on said diaphragm; a plug threaded to said hub having a flat-sided shank; an adjusting member mounted on said shank and movable endwise thereof provided with a locking finger
 15 adapted to engage one of said peripheral grooves; a revoluble supporting plate carried by said plug; and a spring interposed between said plate and button.
7. In a device of the class described, the
 20 combination of a casing provided with inlet and outlet openings separated by a partition with a conically seated port and having cylindrical chambers on opposite sides of said port and in axial alinement therewith connected by an intercommunicating passage terminating at the outer ends of said chambers; a spring pressed valve normally closing said port and provided with a piston member loosely fitting one of said chambers;
 25 a reciprocating member fitted to the other chamber secured to and movable with said valve; a removable member for closing the end of the first mentioned chamber and provided with a port communicating with said intercommunicating passage; a small valve carried by said member, a spring also carried by said member for normally closing said small valve; a diaphragm superimposed upon said removable member and under the
 30 influence of the fluid pressure in said outlet opening; a member threaded to said casing inclosing said removable member and diaphragm and having a cylindrical hub provided with peripheral grooves; a button
 35 resting on said diaphragm; a plug threaded to said hub having a flat-sided shank; an adjusting member mounted on said shank and movable endwise thereof provided with a locking finger adapted to engage one of said peripheral grooves; means for limiting the outward movement of said adjusting member; a revoluble supporting plate carried by said plug; and a spring interposed between said plate and button.
- 55 8. In a device of the class described, the combination of a casing provided with inlet and outlet openings separated by a partition with a conically seated port and having cylindrical chambers on opposite sides of said
 60 port and in axial alinement therewith connected by an intercommunicating passage terminating at the outer ends of said chambers; a spring pressed valve normally closing said port and provided with a piston member loosely fitting one of said chambers;

a reciprocating member fitted to the other chamber and secured to and movable with said valve; a removable cup-shaped member for closing the end of the first mentioned chamber and provided with a port communicating with said intercommunicating passage; a small valve carried by said member; a spring also carried by said member for normally closing said small valve; and adjustable means for controlling the opening of said small valve adapted to be influenced by the fluid pressure in said outlet opening.

9. In a device of the class described, the combination of a casing provided with inlet and outlet openings separated by a partition with a conically seated port and having cylindrical chambers on opposite sides of said port and in axial alinement therewith connected by an intercommunicating passage terminating at the outer ends of said chambers; a spring pressed valve normally closing said port and provided with a piston member loosely fitting one of said chambers; a reciprocating member fitted to the other chamber secured to and movable with said valve; a smaller valve for controlling the flow of fluid through said intercommunicating passage; and adjustable means for regulating the operation of said smaller valve under the influence of the fluid pressure in said outlet opening.

10. In a device of the class described, the combination of a casing provided with inlet and outlet openings separated by a partition with a conically seated port and having cylindrical chambers on opposite sides of said port and in axial alinement therewith connected by an intercommunicating passage terminating at the outer ends of said chambers; a spring pressed valve normally closing said port and provided with a piston member loosely fitting one of said chambers; a reciprocating member fitted to the other chamber secured to and movable with said valve; means for admitting fluid pressure from the inlet opening through the intercommunicating passage to the second mentioned chamber beneath said reciprocating member to open the main valve; and adjustable means under the influence of the fluid pressure in the outlet opening for regulating the movement of said valve and maintaining a predetermined pressure.

11. In a device of the class described, the combination of a diaphragm inclosing cap provided with a cylindrical hub having peripheral grooves at its outer end; a pressure regulating device including a plug threaded to said hub and provided with a flat-sided shank; an adjusting member movable lengthwise of said shank and having a groove engaging finger; and means on the outer end of said shank for limiting the outward movement of said adjusting member.

12. In a device of the class described, the combination of a diaphragm inclosing cap provided with a cylindrical hub having peripheral grooves at its outer end; a pressure regulating device including a plug threaded to said hub and provided with a flat-sided shank; an adjusting member movable lengthwise of said shank and having a groove engaging finger; means on the outer end of said shank for limiting the outward movement of said adjusting member; and means secured to the inner end of said plug coacting with a shoulder on said hub to limit the outward movement of said plug.
13. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
14. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
15. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
16. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
17. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
18. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
19. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
20. In a device of the class described, the combination of a casing having inlet and outlet openings separated by a partition having a conically seated opening therein; a downwardly closing main valve normally closing said opening and held closed by the high pressure fluid; a cylindrical chamber above said valve; a loosely fitting piston therein secured to said valve; a second chamber beneath said valve communicating at the top with the outlet opening; a reciprocating member fitting said second chamber and secured to said main valve; a downwardly opening secondary valve above said piston and controlling a passage from the first chamber to the second chamber with which it communicates at a point beneath said reciprocating member; a pressure regulating spring acting on the upper end of the secondary valve to insert it against the high pressure; and a passage leading from the outlet opening to the lower side of the pressure regulating device to assist in forcing it away from the secondary valve.
